FINGER FOR A CHICKEN PLUCKING MACHINE

Benjamin Levin, 511 Commercial St., Glendale, Calif.

Filed Sept. 9, 1960, Ser. No. 62,076

Term of patent 14 years

(Cl. D11—1)

FIG. 6

FIG. 1

FIG. 2

FIG. 3

FIG. 4

FIG. 5

FIG. 6

FIG. 7

FIGURE 1 is a perspective view of a finger for a chicken plucking machine showing my new design;
FIGURE 2 is a side elevational view thereof;
FIGURE 3 is a bottom view thereof;
FIGURE 4 is a front elevational view thereof;
FIGURE 5 is a rear elevational view thereof;
FIGURE 6 is a cross sectional view taken on the line 6—6 of FIGURE 1; and
FIGURE 7 is a cross sectional view taken on line 7—7 of FIGURE 3.

I claim:

The ornamental design for a finger for a chicken plucking machine, substantially as shown.
